CLAIM

The ornamental design for a gasoline container, as shown and described.

DESCRIPTION

FIG. 1 is a front perspective view of a gasoline container showing our new design;

FIG. 2 is a rear perspective view of the container of FIG. 1;

FIG. 3 is a top plan view of the container of FIG. 1;

FIG. 4 is a right side elevation view of the container of FIG. 1, the undisclosed left side being a mirror image thereof;

FIG. 5 is a bottom plan view of the container of FIG. 1;

FIG. 6 is a front elevation view of the container of FIG. 1; and,

FIG. 7 is a rear elevation view of the container of FIG. 1.
